UNITED STATES PATENT OFFICE.

SOLOMON S. GIPE, OF HERSHEY, PENNSYLVANIA.

CORNER-CUTTING MACHINE FOR BOX BLANKS.

1,416,282.

Specification of Letters Patent. Patented May 16, 1922.

Application filed April 5, 1921. Serial No. 458,819.

To all whom it may concern:

Be it known that I, SOLOMON S. GIPE, a citizen of the United States, residing at Hershey, in the county of Dauphin and State of Pennsylvania, have invented certain new and useful Improvements in Corner-Cutting Machines for Box Blanks, of which the following is a specification.

One object of my invention is to provide an improved machine which will simultaneously cut a plurality of corners from blanks of sheet material, such for example as from cardboard, in order that the blanks may be formed into boxes.

Another object is to so construct my improved machine that it will be capable of cutting blanks of different sizes.

Another object is to so make my improved machine that it will be capable of cutting out corners of different widths and depths.

A still further object is to so arrange the parts of my improved machine that a quick and accurate adjustment may be made for cutting the material as above set forth.

Another object of my invention is to provide means which will be so arranged and operative that there will be no possibility of the sheet material getting out of proper alignment either during the feed or cutting operation.

A further object is to provide improved guiding means which insures proper feed and discharge of the material.

A still further object is to provide an automatic control whereby large quantities of material may be arranged in stack form; the sheets of material being automatically fed and delivered in such manner that it will be deposited in superimposed condition so that it can be easily and quickly removed, when cut, in bundle or stack form.

These objects, and other advantageous ends which will be described hereinafter, I attain in the following manner, reference being had to the accompanying drawings in which

Figure 1 is a side elevation of my improved machine.

Figure 2 is a top plan view of the machine shown in Figure 1.

Figure 3 is an end elevation of the left hand end of the machine as shown in Figure 1.

Figure 4 is an enlarged fragmentary sectional elevation taken on the line 4-4 of Figure 2,

Figure 5 is an enlarged fragmentary longitudinal sectional elevation taken on the line 5-5 of Figure 2,

Figure 6 is an enlarged fragmentary longitudinal section taken on the line 6-6 of Figure 2,

Figure 7 is a transverse sectional elevation taken on the line 7-7 of Figure 6, illustrating the same with one of the bottom cross beams of the main frame omitted,

Figure 8 is a fragmentary sectional plan view taken on the line 8-8 of Figure 7,

Figure 9 is a fragmentary sectional plan view taken on the line 9-9 of Figure 7,

Figure 10 is a fragmentary perspective view showing one of the cutting units together with means for insuring the proper placement of the material to be cut upon the movement of said material into the machine,

Figure 11 is a side elevation illustrating certain of the parts moved into a different position from that illustrated in Figure 10 and showing the action of the several parts upon the approach of the material to the cutting unit and to the automatically movable stop,

Figure 12 is a fragmentary view illustrating means for locking the stop in position and showing the arrangement of the locking means and notched stop,

Figure 13 is an enlarged fragmentary section taken on the line 13-13 of Figure 5,

Figure 14 is an enlarged fragmentary section taken on the line 14-14 of Figure 6, illustrating the sliding connection between the cutter casings and the main bed,

Figure 15 is an enlarged central section taken throughout one of the spring guide band reels which I preferably employ, and

Figure 16 is a face view of a box blank having corners cut therefrom by my improved machine in order to form a box.

Referring to the drawings, 20 represents a main supporting frame which is preferably made of an open construction so as to permit access in different directions to the various supported elements for purposes obvious from the construction hereinafter described. The frame 20 has two upper transverse beams 21 and two lower transverse beams 22. A common superimposed cutter supporting head 23 includes an upper frame 24 which is preferably made substantially rectangular in form as shown in Figure 2; said frame adjacent its four corners having

posts 25 secured thereto by nuts 26. These posts are slideable vertically through the beams 21 and 22. The longitudinally extending frame rails 27 have slots 28 cut there-
5 through of extended length in the direction of said rails 27 through which stud bolts 29 extend. The stud bolts 29 support the opposite ends of two transversely extending bars 30; said bars having slots 31 cut there-
10 through extending in a direction trans-
versely to the length of the slots 28.

Cutters 32 which are preferably made hollow and angular in transverse section are suspended from the bars 30 by bolts 33 which pass through the transverse slots 31 in the bars 30. These cutters 32 are adapted to slide vertically within cutter casings 34; said casings at their bottoms being slidably mounted in longitudinal directions on bed bars 35; there being in the present instance two of said bed bars having portions spaced apart directly under the cutter casings to provide a space 36 to permit the cuttings to fall therethrough as will hereinafter be de-
25 scribed.

The bed bars 35 are supported on the lower beams 22 of the main frame; said lower beams having undercut grooves 37, as clearly shown in Figure 4, in which the lower headed ends 38 of bolts 39 extend; said bolts 39 being secured to the end portions 40 of the bed bars 35 so that said bed bars have trans-
30 verse adjustment. The cutter casings 34 are slightly undercut at their bottoms so as to provide shoulders for abutment with the spaced portions of the respective bed bars 35, and adjusting screws 41, which have right and left handed screw threaded portions, are adapted to engage screw threaded
35 brackets 42 which are secured to the sides of the cutter casings 34 as clearly shown in Figure 6. The cutter casings are also provided with extensions 43 through which bolts 44 pass; said bolts 44 extending into grooves 45 in the bed bars 35. The adjusting screws 41 are provided with worm wheels 46 which are in mesh with worms 47 on a shaft 48; said shaft extending transversely through the machine and provided with hand wheels 49 on opposite sides of the frame whereby it can be manually rotated to adjust the longitudinal positions of the casings and cutters when the bolts 29 and 44 are loosened; it being noted that the shaft 48 is provided
50 with a key-way 50 extending in the direction of its length in which keys 51 in the worms 47 slidably fit. In order to provide trans-
55 verse movement of the cutters and cutter casings I provide the bed bars 35 with screw threaded bearings 52 in which transversely extending screw threaded shafts 53 extend; said screw threaded shafts having sprockets 54 secured thereon over which passes a chain 55 so as to couple said shafts together. By
60 thus operatively coupling the shafts 53 to-

gether they may be simultaneously operated by a hand lever 56 at either side of the main frame 20; said shafts 53 being journaled in bearings 57 in the main frame 20. The cutter supporting head, which includes the 70 frame 24 and transverse bars 30, receives a vertical reciprocating movement during the operation of the machine through the medium of the following structure.

Connecting rods 58 are pivotally connect-
75 ed at the sides of the frame 24 as shown at 59. These connecting rods 58 depend through the frame 20 and at their lower ends are provided with eccentrics 60 on a shaft 61; said shaft having a clutch collar 80 62 slidably keyed thereon and adapted to be moved into engagement with the clutch face 63 on a gear wheel 64; said gear wheel being in mesh with a pinion 65 fixed on the main drive shaft 66; said main drive shaft being 85 driven from any suitable source of power through the medium of a pulley 67 as clearly shown in Figure 9. It will thus be noted that during the rotation of the shaft under certain conditions during the operation of 90 the machine, the eccentrics will operate to move the cutter supporting frame 23 upwardly and downwardly to cause a reciprocation of the cutters 32 within the casings 34.

The opposed portions of the cutter casings 95 are cut away adjacent their bottoms to provide mouths 68; the portions 69 of said cutter casings below said mouths being provided with cutting blades 70 adapted to contact with the cutting blades 71 of the cutters 100 32 to cut the corners of sheet material such as cardboard blanks 72, as illustrated in dot-and-dash line, when said blanks are positioned under the cutters by mechanism hereinafter described.

Supporting rails 73 which are secured on the bed bars 35, as clearly shown in Figure 7, are positioned so that their upper surfaces are flush with the upper surfaces of the bottom portions 69 of the cutter casings as 110 clearly shown in Figures 7 and 10; the portions 69 of said cutter casing being preferably curved as shown at 74 to permit said side rails 73 to extend therein so that an accurate sliding relation is rendered possible 115 when it is necessary to adjust the cutters and cutter casings longitudinally. I also preferably provide central supporting rails 75 as clearly shown in Figure 7 for supporting the central portions of the material to be cut 120 and these central supporting rails are mounted on legs or brackets 76 which in turn are secured on the lower beams 22 of the main frame 20. The opposite ends of the central rails 75 are provided with adjustable extensions 77 and the side supporting rails 73 are also provided with adjustable extensions 78 at their opposite ends as clearly shown in Figure 6.

My improved machine as illustrated is 130

capable of simultaneously cutting the four corners of a number or group of superimposed blank sheets and I have provided means for automatically feeding the sheet material under the cutters and I will now describe said latter mentioned means. A bar 79 is slidable transversely upon an extension 80 of the base of the frame 20 as clearly shown in Figures 1 and 2 and this 5 bar 79 has stanchion posts 81 which are secured at their upper ends to an auxiliary frame 82; said auxiliary frame being slidably mounted on the lower front beam 22 of the frame 20. Thus the stanchion posts 81, 10 bar 79 and auxiliary frame 82 may be slidably moved transversely of the frame 20 by merely pushing laterally upon the same. 15 Two tables 83 and 84 are slidable vertically on the posts 81 as clearly shown in 20 Figures 1 and 3; there being four posts 81 as illustrated and arranged in pairs upon which the tables respectively slide. These 25 tables are adapted to receive the sheet material in stack form as indicated at 85 in Figure 1 and these tables as they are moved into alignment with the central portion of the frame, such for example as in the position occupied by the table 83 in Figure 3, are adapted to be automatically moved upwardly by a step by step movement so as to 30 present the uppermost sheets on a level with the tops of the supporting rails 73 and 75. Since the mechanism for intermittently moving the tables 83 and 84 upwardly is 35 identical, I will describe but one of the mechanisms in detail and it will be understood that the mechanism for raising the other table is substantially the same.

A shaft 86 has sprockets 87 secured there- 40 to over which pass chains 88. These chains are connected at 89 to the bottom portion 90 of the table on opposite sides thereof. Levers 91 have pawls 92 thereon as shown in 45 Figure 3, and these pawls are adapted to engage the teeth of ratchet wheels 93 on the shaft 86. The levers 91 have slots 94 therein through which bolts 95 in links 96 extend; 50 said bolts being adapted to be secured in any position within the length of the slots. The links 96 are connected with arms 97 which are pivotally connected to the slidable auxiliary frame 82 as shown in Figure 1 and the arms 97 have headed pins 98 projecting laterally therefrom over which the forked 55 ends 99 of connecting bars 100 are adapted to extend; said connecting bars being pivotally connected at 101 to arms 102 which are secured to a rock shaft 103 which is journaled in the main frame 20.

60 An angularly disposed arm 104 is connected to a link rod 105; said link rod at its bottom being pivotally connected to a lever 106 which is pivoted at 107 on the frame 20. The opposite end of the lever 106 is adapted 65 to be raised by means of a pin 108 on a wheel

109 which is secured to a rotatable shaft 110. This shaft 110 has a gear wheel 111 fixed thereon which meshes with a pinion 112 which is rotatably secured to the gear wheel 64. Thus it is obvious that when the shaft 70 110 is rotated, the lever 106 will be intermittently swung and by the above described connection the connecting bars 100 will swing the arm 97 so as to pull the link 96 and to cause the sprocket wheels 87 to be intermittently rotated so as to lift the table 83 in a step by step movement. A spring 113 connects the arm 97 with the auxiliary frame 82 and tends to return the parts to their normal positions after having been moved by 80 the pin 108 to actuate the pawls and ratchets to lift the table. As shown in Figure 1, a detent pawl 93^a is positioned for engagement with the ratchet 93 to prevent the table 83 from accidentally moving downward after 85 each upward movement.

It is apparent that by moving the bolts 95 into various portions of the slots 94 that the amount of movement imparted to the ratchet wheels can be varied so as to effect greater 90 or less intermittent lifting movements of the table. I also preferably provide a stop for the return movement of the arms 97 and in the present instance I have illustrated said stop as consisting of a screw 114 mounted in 95 a projection 115 which extends from the side of the auxiliary frame 82.

A feed carriage 116 is slidably mounted on a rail 117; said rail 117 being angular in cross section to prevent swinging movement 100 of the feed carriage thereon. The feed carriage has a depending feeding finger 118 which presents a shoulder 119 to the forward face of the bundle or stack of sheets while resting on the table 83 and during the movement of the carriage inwardly by mechanism hereinafter described, the shoulder 119 of the finger 118 will move a number of the sheets into the machine so that the sheets will slidably rest on the supporting rails 73 110 and 75. The carriage 116 has a spring pressed latch 120 pivotally mounted thereon at a spaced distance from the finger 118 and this latch, as clearly shown in Figure 5, 115 serves to push the sheets, which have been previously cut, out of the machine; said cut sheets being slidable on the rails 73 and 75 and out upon receiving means which will hereinafter be described; it being noted that the sheets as they are fed into the machine 120 will pass into the mouths or cut-away portions 68 of the cutter casings up in a position directly under the cutters as the latter descend due to the connecting means above described. The means which moves the carriage for the feeding operation will now be 125 described.

A conveyor casing 121, which is clearly shown in Figures 5 and 13, is secured to the upper beams 21 of the frame 20 in a position 130

directly above the carriage rail 117. This casing encloses a conveyor belt or chain 122 which passes around two sprocket wheels 123 and 124. The sprocket 123 is connected 5 to a rotatable driving shaft 125 and the sprocket 124 is connected to a stud shaft 126 which has its ends in bearings 127 which are connected to an adjustable bracket 128 so that the stud shaft 126 can be moved bodily 10 away from the shaft 125 and thereby take up any slack which occurs in the chain conveyor 122.

Two guide rods 129 are spaced apart within the conveyor casing 121; said guide rods 15 at their opposite ends being secured in fixed stops 130 and 131. A connecting head 132 has holes therein through which the guide rods 129 extend so that the connecting head 132 is slidable backwardly and forwardly 20 along the guide rods 129 as clearly shown in Figure 5. The connecting head 132 also has holes through which the opposite runs of the conveyor chain are adapted to pass. The lower end of the connecting head is 25 connected by a pivoted rod 133; said rod extending through a collar 134 which is pivoted at 135 to a lug 136 on the carriage 116. A tapered gland nut 137 surrounds the rod 133 and fits within a tapped recess in the collar 134 so that when the gland nut is 30 tightened, it will clamp upon the rod 133 and thereby secure the rod to the collar 134. By thus pivoting the collar 134 on the lug 136 there is a compensation for any variation 35 in the alignment of the several parts and a free and smooth actuating movement results. The connecting head 132 has opposite side portions which are spaced apart to provide an upright chamber or guide way 40 138 in which is slidable a carrier bolt 139; said carrier bolt being of such length as clearly shown in Figure 13 that when moved upwardly its top will be in the path of movement of a projection 140 on the conveyor 45 chain 122 and the bottom of the carrier bolt 139 will be above the level of the lower run of the chain 122 so that the upper run of the chain will move the connecting head 132 in the direction of the upper arrow as shown 50 in Figure 5. If, on the other hand, the carrier bolt 139 is moved downwardly, the projection 140 when traveling on the lower run of the chain will engage the lower portion 55 of the carrier bolt and move the connecting head in an opposite direction. Thus it is seen that if the carrier bolt 139 is alternately moved upwardly and downwardly that the connecting head will receive a reciprocating movement which it will impart 60 to the carriage 116. I accomplish this raising and lowering movement of the carrier bolt 139 by inserting a shift bolt 141 within the connecting head; said shift bolt having an inclined slot 142 through which a pin 65 143 in the carrier bolt 139 projects. The

shift bolt 141 is of greater length than the width of the connecting head 132 and the arrangement is such that when the connecting head is moving in one direction, such for example as the direction of the upper arrow 70 in Figure 5, one end of the shift bolt will strike the stop 131 at the end of the guide rods 129 and a slight continued movement of the connecting head in said direction will cause the carrier bolt 139 to be lowered due 75 to the pin and slot connection above specified and the top of the carrier bolt will be moved out of the path of the projection 140 on the upper run of the chain 122 and the connecting head will remain stationary until 80 said projection passes to the lower run where it will engage the lower portion of the carrier bolt and move the connecting head in an opposite direction and thereby cause the shift bolt to engage the stop 130 to cause 85 the carrier bolt to be again raised and in this manner the reciprocating movement of the connecting head and carriage is accomplished.

In order to prevent the inertia of the 90 sheets of material while being moved into the machine, from carrying the sheets beyond the proper position below the cutters, I provide the following mechanism as clearly shown in Figures 5, 10, 11 and 12. Adjacent 95 the rear cutter casings I mount plates 144; said plates being positioned in undercut grooves 145 in the bottom portions of the cutter casings 134 and these plates 144 are adjustably connected longitudinally to the 100 cutter casings by means of set screws 146. Limiting stops 147 from the rear edges of the sheets of material are slidable vertically between guiding portions 148 of the plates 144; said limiting stops having shoulders 149 105 for engagement with the portions 148 to limit their downward movement to a position with their top edges flush with the tops of the rails 73. Strip springs 150 are connected to the plates 144 and normally serve 110 to move the limiting stops 157 upwardly into a position so as to form an abutment for the ends of the sheets as clearly shown in Figure 11. The stops 147 have notches 115 151 therein into which locking bolts 152 are 115 adapted to move when the stops are in their lowermost or normal positions such for example as shown in Figures 10 and 12. These locking bolts are moved into said locking positions by springs 153. Trip levers 154 120 are pivotally connected at 155 to the plates 144 and said trip levers have independently pivoted ends 156 which swing in one direction relatively to the body portions of the trip levers. These ends 156 are adapted to 125 engage back shoulders 157 on the locking bolts 152 when the trip levers are in their upright or vertical positions, such as shown in Figure 10. When in the upright positions, the tops of the trip levers 154 are in 130

the path of movement of the sheets and when the ends of the sheets strike the upper parts of the trip levers, the trip levers will be swung on their pivots 155 against the action 5 of springs 158 and the ends 156 will slide the locking bolts 152 against the action of the springs 153 and thereby withdraw the locking bolts from the notches 151. The springs 150 will then act to raise the limiting stops 147 so as to cause the sheets of material to stop at a proper position under the cutters. When the cutters descend to 10 cut the corners out of the sheets, arms 159 engage the tops of the stops 147 and push them downwardly until the ends of the locking bolts 152 move into the notches 151 and thereby hold the limiting stops 147 down in their normal position during the ejection of the cut sheets. After the sheets have moved 15 from over the top of the trip levers 154, the springs 158 will move said trip levers from their upright positions and the ends 156 will swing on their pivots so as to permit said ends to again position themselves in 20 back of the shoulders 157 on the lock bolts 152. The arms 159 on the shoulders may be adjusted in the event of the requirement of adjustment of the limiting stops 147 by movement of the plates 144 by sliding the 25 arms in the undercut grooves 160 as is clearly obvious in the showing of Figure 10; there being a set screw 161 to secure the arm in its adjusted position.

I preferably mount rollers 162 in a bracket 30 163 for the purpose of engagement with the uppermost sheets as a number of the sheets are pushed into the machine by the carriage finger 118 and this bracket 162 is supported on a cross bar 164 on an extension 165 of 35 the main frame 20; said construction being clearly illustrated in Figures 1 and 3.

In order to prevent lateral shifting movement of any of the sheets while they are passing into the machine, I provide flexible 40 strips or bands 166 which are arranged parallel to each other and in pairs; one pair being arranged between the cutter casings while the other pair is positioned forward of the cutter casings as clearly shown in 45 Figure 5. Each band of the central pair has its forward end secured to a slide 167 which is adjustably mounted in undercut grooves in side portions of the cutter casings as clearly shown in perspective view in 50 Figure 10; the slides being secured by means of set screws 168 so that the bands can be moved apart or together according to the width of the sheets passing into the machine and any small adjustment desired can be 55 made without varying the adjustment of the cutting elements.

The rear ends of the strips 166 are wound upon reels 169 such as shown in detail in Figure 15 and these reels are preferably 60 provided with spiral springs 170 which are

mounted in casings 171 adjacent their ends; said springs normally tending to wind the strips on the reels so that if the cutting units are moved toward each other in a direction longitudinally of the springs that 70 the springs 170 will turn the reels to take up a part of the strips equal to the distance which the cutting units have been moved.

When the cutting units are moved apart longitudinally of the machine, the reels will 75 be rotated to provide an additional length of the strip therebetween and the spring 170 will be subsequently tightened and placed under greater tension. In order to prevent any lateral shifting movement of 80 the sheets as they pass between the strips from bowing the strips to the extent of turning the reels, I provide clamping bolts 172 in the reels; said clamping bolts having thumb nuts 173 which when tightened will 85 serve to jam the parts together to prevent the rotation of the reels. The forward pair of strips 166 are made substantially similar to the central pair just described with the exception that the reels for the forward 90 pair of strips are mounted in standards 174. The standards 174 are slidably mounted in undercut grooves 175 which extend transversely of the beds 35 as shown in Figure 4; said standards being secured in any desired 95 transverse position by means of set screws 176. It will be noted that the reels for the central pair of strips are also secured to slides 177 as shown in Figure 6 and these 100 slides are secured in any desired transverse position by means of set screws 178. In this manner the guide strips 166 can be bodily adjusted toward or from each other to accommodate and provide a channel through 105 which the sheet material passes and the connection of the reels with the strips permits the cutter casings and cutters to be moved toward or from each other to cut the corners out of sheets of various lengths; the strips 166 being present at all times to serve 110 as guides during the cutting action. The pieces as they are cut from the corners of the sheets will fall down through the lower portions of the cutter casings and through the space 36 between the separated parts of 115 each of the bed bars.

As a means for conveying these cuttings from the machine, I provide conveyor belts 179 at the lower portions of the spaces 36; said conveyor belts passing over pulleys 180 120 and 181, which are respectively mounted on shafts 182 and 183. The pulleys 181 are slidably keyed to the shaft 183 and the shaft 183 is driven by a belt 184 which passes around a pulley 185 on said shaft 183. The belt 184 is driven by a pulley 186 on the shaft 110 and it will be noted that the cuttings which fall through the spaces 36, drop on the upper runs of the belts 179 and are conveyed rearwardly and deposited on a 130

transversely extending conveyor belt 187 which is mounted below the conveyor belts 179. The conveyor belt 187 passes around pulleys 188 and 189 which are respectively supported on rods 190 and 191. A bevel gear 192 is secured to the shaft 191 and this bevel gear 192 meshes with another bevel gear 193 on a transversely extending shaft 194 as clearly shown in Figures 4, 7 and 8. The shaft 194 has a pulley 195 thereon which is driven by a belt 196 from a pulley 197 on the shaft 183. It is thus obvious that the conveyor belts 179 and 187 serve to convey the cuttings irrespective of the positions of the cutting elements and if desired a suitable receptacle (not illustrated) can be placed under the projecting end portion 198 of the conveyor belt 187; said projecting portion being illustrated in Figures 3, 7 and 8. The shaft 125 which drives the conveyor chain 122 for the feeding carriage 116, may be driven by any suitable mechanism and in the present instance I have illustrated the shaft 125 at a position outside of the casing 121 provided with a bevel gear 199 which meshes with a bevel gear 200 on a shaft 201; said shaft within its length being provided with a universal joint 202 as clearly shown in Figure 6. The lower end of the shaft 201 is provided with a bevel gear 203 which meshes with another bevel gear 204 on the shaft 66. Thus during the rotation of the shaft 66 the conveyor chain will be operated for the purpose above described.

I provide the following mechanism for receiving the cut sheets. The bottom of the main frame 20 has a rear extension 205 upon which is slidably transversely a bar 206. The bar 206 is constructed similar to the bar 79 and has two sets of posts 207 which slidably support receiving tables 208 and 209; either of the receiving tables 208 and 209 being adapted to be moved into a position centrally of the machine by pushing the bar 206 laterally. Considering that one of the tables 208 and 209 is in a position located centrally within the width of the machine as clearly shown in Figure 2 and in a raised position with its top substantially on a level with the tops of the rails 73 and 75, the latch 120 will serve to push the cut sheets upon the table and it is obvious that before the next group of sheets are pushed outwardly by the latch 120 that the table must be depressed so that the next group of sheets will be deposited upon the top of the sheets which were previously deposited upon said receiving table. For the above mentioned purpose I provide the following mechanism.

The tops of the posts 207 have an auxiliary frame 210 which slides on the rear beam 22 as shown in Figure 1 and this auxiliary frame 210 has sprocket wheels 211 thereon

over which chains 212 pass; said chains at one end being connected to the bottom portion of the respective tables while the opposite ends of the chains are provided with weights 213; said weights serving to move the receiving tables upwardly when permitted to do so; it being noted that certain of the sprockets 211 are provided with ratchet wheels 214 for the engagement with pawls 215; said pawls serving when the tables are depressed to prevent the tables from rising due to the action of the weights 213; said ratchet wheels and pawls being illustrated in Figures 1 and 2.

A presser foot 216 is mounted on a rod 217 which is slidable vertically in a rear extension 218 of the frame 20. An arm 219 is secured to a shaft 220 in the frame extension 218 and the rear end of the arm 219 is connected to the top of the rod 217 through the medium of a link 221. The shaft 220 has another arm 222 secured thereon and said latter arm is connected by an eccentric rod 223; said eccentric rod being movable by an eccentric 224 on the shaft 110; the timing being such that after the delivery of each group of cut sheets that the presser foot 216 will move downwardly upon the uppermost sheet on the receiving table and will cause the entire stack of sheets to move downwardly to make room at the top for the next group of cut sheets; the pawls 215 serving to prevent upward movement of the receiving table and stacked sheets when the presser foot is again raised to its normal position.

It will be understood that each of the receiving tables is equipped with the mechanism just described in connection with the table 208 in its position as shown in Figures 1 and 2 and it is therefore believed unnecessary to again describe this detail of construction in connection with the table 209. In order to provide for the proper timing and dwell of the several parts so that they will operate in a manner consistent with that above described, I provide the shaft 110 with a cam 225 which has an internal cam groove 226 in which a projection 227 on an arm 228 extends; said arm 228 being pivoted at 229 on the bracket 230 as clearly shown in Figure 9. The opposite end of the arm 228 is yoked to embrace the clutch collar 62; said clutch collar having an annular groove 231 into which pins 232 in the yoked portion of the arm 228 project. Thus upon rotation of the cam 225 the clutch collar 62 will be alternately moved into and out of engagement with the clutch face 23 of the gear 64 and the cutting head will be operated when the clutch collar is in operative connection with the gear 24; the arrangement being such that after the cutting head has descended and again risen that the clutch collar will be automatically moved into an inoperative po-

sition as is obvious from the construction illustrated and above described.

By having the two tables 83 and 84 adjacent the feed end of the machine while one 5 of the tables is in a position to permit the feeding of the sheets therefrom, the other table can be stacked with blank sheets and when the table 83 as shown in Figure 2 is empty the bar 79 can be pushed so as to bring 10 the filled table 84 into feeding alignment; it being noted that it is necessary to raise the connecting bars 100 so as to disengage with the arms 97 for one table and then connect the bars 100 with the pins 98 for operating 15 the other table. Thus it is always possible to keep the tables 83 and 84 stacked with blank sheets so that no time will be lost in the stopping of the machine.

In similar manner by having two receiving 20 tables 208 and 209 when one of the tables becomes filled, the other table which has previously been emptied can be pushed into receiving position merely by sliding the bar 206 transversely along the extension 205 of 25 the base.

It is further obvious that by the provision of the frame 24, cross bars 30 and bed bars 35, the cutting elements can be moved into various positions to readily accommodate 30 cardboard or other sheet blanks of various lengths and widths and for this reason my improved machine is of particular advantage in the art since it is capable of adjustment to suit various requirements.

35 While I have described my invention as taking a particular form, it will be understood that the various parts of my invention may be changed without departing from the spirit thereof, and hence I do not limit myself to the precise construction set forth, but consider that I am at liberty to make 40 such changes and alterations as fairly come within the scope of the appended claims.

Having thus described my invention, 45 what I claim as new and desire to secure by Letters Patent is:—

1. A machine of the character described including a cutter casing having an opening providing a mouth extending laterally 50 therein; a cutter slidably mounted in said casing and having a cutting portion movable across said mouth; guiding means positioned with its top surface approximately flush with the bottom portion of said mouth; and 55 means for feeding sheet material along said guiding means and into said mouth whereby the cutter is operative to cut pieces out of said sheet material.

2. A machine of the character described 60 including a main supporting frame; bed bars supported on said frame and adjustable transversely of the length thereof; a cutting head; cutters connected to said head and adjustable in the direction of the width and 65 length of said machine; cutter casings sup-

ported by said bed bars in which the cutters respectively slide; means for feeding sheet material between said cutters and casings; means for moving said cutting head, said bed bars having portions spaced apart 70 through which the cuttings fall; and conveyor belts below said space adapted to receive the cuttings.

3. A machine of the character described including two sets of cutting units spaced 75 apart; means for feeding sheet material in a path between the sets of cutting units; guiding means between the units of each set; and means for reducing the length of said guiding means when the units of each set are 80 moved together; and for permitting the lengthening of said guiding means when the units of each set are moved apart.

4. A machine of the character described including two sets of cutting units spaced 85 apart; means for feeding sheet material in a path between the sets of cutting units; flexible guiding strips between the units of each set; and means upon which said flexible guiding strips may be wound when the units 90 of each set are moved together and from which said flexible strips can be unwound when the cutting units are moved apart.

5. A machine of the character described including two sets of cutting units spaced 95 apart; means for feeding sheet material in a path between the sets of cutting units; flexible guiding strips between the units of each set; means upon which said flexible guiding strips may be wound when the units of each 100 set are moved together and from which said flexible strips can be unwound when the cutting units are moved apart; and means for permitting the adjustment of said strips toward or from each other to vary the width of 105 the path through which said sheet material can pass.

6. A machine of the character described including cutting units spaced apart; a flexible guiding strip extending between said cutting units; and a reel upon which said strip can be wound when the cutting units are moved toward each other and from which the strip can be unwound when the cutting units are moved apart.

7. A machine of the character described including cutting units spaced apart; a flexible guiding strip extending between said cutting units; a reel upon which said strip can be wound when the cutting units are 115 moved toward each other and from which the strip can be unwound when the cutting units are moved apart; and means for preventing accidental unwinding movement of said reel.

8. A machine of the character described including cutting units spaced apart; a flexible guiding strip extending between said cutting units; a reel upon which said strip can be wound when the cutting units are 120 moved toward each other and from which the strip can be unwound when the cutting units are moved apart; and means for preventing accidental unwinding movement of said reel.

5 moved toward each other and from which the strip can be unwound when the cutting units are moved apart; and means for automatically rotating said reel when the cutting units are moved together whereby the length of said strip is shortened.

9. A machine of the character described including cutting units spaced apart; a flexible guiding strip extending between said cutting units; a reel upon which said strip can be wound when the cutting units are moved toward each other and from which the strip can be unwound when the cutting units are moved apart; and a spring connected to said reel and operative to wind a portion of said strip thereon when the units are moved together, said spring being placed under tension by the rotation of said reel when the units are moved apart; substantially as described.

10. A machine of the character described including a cutter casing having an opening providing a mouth extending laterally therein; a cutter slidably mounted in said casing and having a cutting portion movable across said mouth; guiding means positioned with its top surface approximately flush with the bottom portion of said mouth; means for feeding sheet material along said guiding 15 means and into said mouth whereby the cutter is operative to cut pieces out of said sheet material; and a bed bar having portions spaced apart under said cutter casing.

11. A machine of the character described including a main supporting frame; two bed bars extending longitudinally of said frame and being movable transversely therein; cutter casings supported by said bed bars and movable longitudinally thereof; mechanical means for moving said bed bars transversely toward and from each other whereby said cutter casings receive said movement; cutters fitting said casings; a superimposed cutting head having a frame 20 forming a common connecting means for said cutters; means for connecting said cutters with the cutting head whereby the cutters are capable of adjustment in conjunction with said casings and bed bars; means 25 for actuating said cutting head to move the cutters within the casings; and means for feeding sheet material between the cutters and casings.

12. A machine of the character described including a main supporting frame; two bed bars extending longitudinally of said frame and being movable transversely therein; cutter casing supported by said bed bars and movable longitudinally thereof; mechanical 30 means for moving said bed bars transversely toward and from each other whereby said cutter casings receive said movement; cutters fitting said casings; a superimposed cutting head having a frame forming a common connecting means for said cutters;

means for connecting said cutters with the cutting head whereby the cutters are capable of adjustment in conjunction with said casings and bed bars; means for actuating said cutting head to move the cutters within the 70 casings; and means for feeding sheet material between the cutters and casings.

13. A machine of the character described including cutter casings having openings providing mouths extending laterally therein; cutters slidably mounted in said casings and having blades movable across said mouths; guiding rails positioned with their top surfaces substantially flush with the bottom portions of said mouths; and means for 80 feeding sheet material along said guiding rails and into said mouths whereby the cutters are operative to cut pieces out of said sheet material.

14. A machine of the character described including cutter casings having openings providing mouths extending laterally therein; cutters slidably mounted in said casings and having blades movable across said mouths; guiding rails positioned with their 90 top surfaces substantially flush with the bottom portions of said mouths; means for feeding sheet material along said guiding rails and into said mouths whereby the cutters are operative to cut pieces out of said sheet 95 material; and a bed bar having portions spaced apart under said cutter casing.

15. A machine of the character described including a supporting structure; a reciprocating cutter movable relatively to said supporting structure; means for feeding sheet material into the path of cutting movement of said cutter; a limiting stop for said sheet material; and means movable by said sheet material to effect the movement of said limiting stop into a position to prevent the inertia of said sheet material from carrying it past a predetermined position relatively to the cutter.

16. A machine of the character described including a supporting structure; a reciprocating cutter movable relatively to said supporting structure; means for feeding sheet material into the path of cutting movement of said cutter; a limiting stop for said sheet 110 material; means movable by said sheet material to effect the movement of the limiting stop into a position to prevent the inertia of said sheet material from carrying it past a predetermined position relatively to the cutter; and means movable in conjunction with said cutter adapted to return said limiting stop to its inoperative position.

17. A machine of the character described including a supporting structure; a reciprocating cutter movable relatively to said supporting structure; means for feeding sheet material into the path of cutting movement of said cutter; a limiting stop for said sheet material having a notch therein; a bolt mov- 125

able into said notch; a trip lever adapted to be moved by said sheet material and operative to withdraw the bolt from said notch in the limiting stop; and means for automatically moving said limiting stop when thus released into a position to stop the movement of said sheet material in a predetermined position relatively to the cutter.

18. A machine of the character described including a supporting structure; a reciprocating cutter movable relatively to said supporting structure; means for feeding sheet material into the path of cutting movement of said cutter; a limiting stop for said sheet material; and means movable by said sheet material to effect the movement of said limiting stop into a position to prevent the inertia of said sheet material from carrying it past a predetermined position relatively to the cutter, said cutter and limiting stop being adjustable in conjunction with each other relatively to the length of said supporting structure.

19. A machine of the character described including a supporting structure; a reciprocating cutter movable relatively to said supporting structure; means for feeding sheet material into the path of cutting movement of said cutter; a limiting stop for said sheet material; and means movable by said sheet material to effect the movement of said limiting stop into a position to prevent the inertia of said sheet material from carrying it past a predetermined position relatively to the cutter, said cutter and limiting stop being adjustable independently of each other relatively to the length of the supporting structure.

20. A machine of the character described including a supporting structure; a cutter casing adjustable in the direction of the length of said supporting structure; a cutter movably mounted in said casing; a plate adjustably mounted on said cutter casing; means for feeding sheet material lengthwise of the supporting structure into the path of the cutter; a limiting stop movably mounted on said plate and having a notch therein; a lock bolt on said plate; a spring for moving said lock bolt into engagement with the notch of the limiting stop; a trip lever adapted to be moved by said sheet material to move said lock bolt out of said notch; and a spring for moving said limiting stop into a position to arrest the movement of said sheet material in a predetermined position relatively to said cutter.

21. A machine of the character described including a supporting structure; a cutter casing adjustable in the direction of the length of said supporting structure; a cutter movably mounted in said casing; a plate adjustably mounted on said cutter casing; means for feeding sheet material lengthwise of the supporting structure into the path of

the cutter; a limiting stop movably mounted on said plate and having a notch therein; a lock bolt on said plate; a spring for moving said lock bolt into engagement with the notch of the limiting stop; a trip lever adapted to be moved by said sheet material to move said lock bolt out of said notch; and a spring for moving said limiting stop into a position to arrest the movement of said sheet material in a predetermined position relatively to said cutter, said lock bolt having a shoulder with which said trip lever engages; a spring for returning said trip lever to its normal position, said trip lever having a pivoted end independently movable thereon to permit it to move into engagement with said shoulder during the return movement of the trip lever.

22. A machine of the character described including a main supporting frame; bed bars supported on said frame and adjustable transversely of the length thereof; a cutting head; cutters connected to said head and adjustable in the direction of the width and length of said machine; cutter casings supported by said bed bars in which the cutters respectively slide, said cutter casings having open bottoms and side openings above said bottoms; means for feeding sheet material so that parts thereof will pass into said side openings; and means for moving said cutting head, said bed bars having portions spaced apart below said bottoms of the cutter casings to provide a space through which the cuttings fall.

23. A machine of the character described including two bed bars; means operative to simultaneously move said bed bars toward or from each other; cutting units supported on said bed bars; common means for moving said cutting units transversely to the direction of movement of said bed bars, said cutting units including casings with cutters movable therein, said casings having opposed openings providing mouths through which said cutters pass; supporting rails having portions adjacent the lower parts of said mouths; and means for feeding sheet material along said rails and through said mouths of the casings.

24. A machine of the character described including bed bars; means for moving said bed bars toward and from each other and including screw threaded shafts having certain portions of their threads pitched at opposite angles and engaging their screw threaded portions on the bed bars; cutting units slidably mounted on said bed bars; and means for moving said cutting units on said bed bars in a direction transversely to said movement of the bed bars; and conveyor belts movable in conjunction with said bed bars and adapted to receive cuttings from said cutting units as material is fed thereto.

25. In a machine of the character described including means for acting upon the sheets as they are fed therein; means for moving said sheets out of the machine after being acted upon; a plurality of receiving tables, and common means for movably supporting said tables adapted to be shifted to move any of the tables under the sheets as they are moved out of the machine.
- 10 26. A machine of the character described including means for acting upon a number of sheets as they are fed therein; means for moving said sheets out of said machine after being acted upon; a plurality of receiving tables; common means for movably supporting said receiving tables and adapted to be shifted so as to move any of said tables under the sheets as they are moved out of the machine whereby the sheets will be deposited thereon; and means intermittently movable into engagement with the uppermost sheets to cause the tables to be lowered to make room at the top of the pile of sheets for other sheets as they are moved out of the machine.
- 15 27. A machine of the character described including a feeding carriage adapted to feed sheets of material into the machine; a conveyor belt; a connecting head; means connecting said head with said carriage; a carrier bolt in said head; a shift bolt in said head; means on said conveyor belt adapted to engage the opposite ends of said carrier bolt when moved into the path of the runs of said conveyor belt by said shift bolt; and means forming stops for abutment with said shift bolt to alternately connect said cross
- 20 head to the opposite runs of said belt through the medium of said carrier bolt upon alternate engagement with said shift bolt with said stops.
- 25 28. A machine of the character described including a feeding carriage adapted to feed sheets of material into the machine; a conveyor belt; and means for operatively connecting said carriage with the opposite runs of said belt whereby the carriage will receive a reciprocating movement.
- 30 29. A machine of the character described including a feeding carriage; a reciprocating connecting head; a rod pivotally connected to said head; a lug on said carriage; a collar pivotally mounted on said lug and through which said rod passes; and means for securing said rod to the collar.
- 35 30. A machine of the character described including a feeding carriage; a reciprocating connecting head; a rod pivotally connected to said head; a lug on said carriage; a collar pivotally mounted on said lug and through which said rod passes; and means for securing said rod to the collar, said latter means including a tapered gland nut surrounding said rod and adapted to fit in a tapped opening in said collar whereby when the nut is tightened it will clamp said rod.
- 35 In testimony whereof I have signed my name to this specification in the presence of two subscribing witnesses.
